UNITED STATES PATENT OFFICE.

STANLEY F. HANZEL, OF CHICAGO, ILLINOIS.

DESIGN FOR A PLAYING CARD.

Application filed October 18, 1923. Serial No. 7,531. Term of patent 3½ years.

To all whom it may concern:

Be it known that I, STANLEY F. HANZEL, a citizen of the United States, residing at Chicago, in the county of Cook and State of Illinois, have invented a new, original, and ornamental Design for Playing Card, of which the following is a specification, reference being had to the accompanying drawings, forming part thereof.

The figure is a plan view of a playing card, showing my new design.

I claim:

The ornamental design for a playing card, as shown.

STANLEY F. HANZEL.
